US00D941262S

(12) **United States Design Patent** (10) **Patent No.:** **US D941,262 S**
Brunner et al. (45) **Date of Patent:** **** Jan. 18, 2022**

(54) **HEADSET**

(71) Applicant: **Apple Inc.**, Cupertino, CA (US)

(72) Inventors: **Robert D. Brunner**, Glen Ellen, CA (US); **Christopher Kuh**, San Francisco, CA (US)

(73) Assignee: **Apple Inc.**, Cupertino, CA (US)

(**) Term: **15 Years**

(21) Appl. No.: **29/795,780**

(22) Filed: **Jun. 21, 2021**

Related U.S. Application Data

(60) Continuation of application No. 29/706,360, filed on Sep. 19, 2019, now Pat. No. Des. 922,978, which is a continuation of application No. 29/642,633, filed on Mar. 30, 2018, now Pat. No. Des. 860,969, which is a continuation of application No. 29/574,209, filed on Aug. 12, 2016, now Pat. No. Des. 814,438, which is a continuation of application No. 29/504,827, filed on Oct. 9, 2014, now Pat. No. Des. 764,435, which is a continuation of application No. 29/464,539, filed on Aug. 18, 2013, now Pat. No. Des. 716,760, which is a division of application No. 29/426,082, filed on Jun. 29, 2012, now Pat. No. Des. 691,112, which is a continuation-in-part of application No. 29/410,585, filed on Jan. 9, 2012, now Pat. No. Des. 698,749.
